UNITED STATES PATENT OFFICE.

FREDERICK W. SPERR, JR., OF PITTSBURGH, PENNSYLVANIA, ASSIGNOR TO THE KOPPERS COMPANY, A CORPORATION OF PENNSYLVANIA.

COKING PROCESS.

Application filed September 12, 1918, Serial No. 253,684. Renewed October 15, 1924.

My invention relates to processes for coking liquefiable bituminous material, and has for a primary object the production of low-ash coke from pitch in a substantially continuous mass-treatment process, but may also be applicable to other liquefiable bituminous materials such as tar, asphalt, petroleum residue, etc.; and the invention has for other objects such other improvements or advantages of method and operation as may be found to obtain in the processes hereinafter described and claimed.

In the accompanying drawings, showing in a conventional manner a form of apparatus that may be employed, in practicing the process, without limiting the invention to such specific illustrative embodiment, Fig. 1 is a conventional vertical section through a series of vertical masonry retorts adapted to the practice of the processes, and Fig. 2, is a conventional vertical section taken at right angles to Fig. 1, through a battery of series of such retorts. Like reference numerals indicate like parts in all of the drawings.

The vertical retorts 10 are formed with masonry partitions 8 masonry walls 9 containing horizontal heating-flues 11, 12, 13 and 14, the successively lower flues being adapted to be maintained at successively higher temperatures, so that the upper zones of the retorts are less highly heated than the zones down toward and somewhat below their middle. The bottom zone of the retort is below the level of the lowest heating flue, so that the coked material toward the bottom of the retort will cool somewhat as it reaches the rotary discharge device 15 that forms the discharge-bottom of the retort and delivers the coke upon the conveyor 16. Each retort is capped with a lid 17 and has an outlet 18 to carry off the evolved gasses and vapors, such outlets of rows of the retorts being in series and leading to the collecting main 19.

In starting operation, each retort is filled to about the level 20 with ordinary coke. The liquefiable bituminous material, such as pitch, is liquefied, or kept liquid, in the tank 21, heated with the steam coils 22, and the melted pitch is led from such tank through the pipe 23 that has branches 24 extending downward through the lids of the retorts and each controlled by a valve 25. The liquid pitch is allowed to flow into the re-

torts, penetrating into the coke mass and forming a rather thick layer on top of it, up to the level 26. This zone, from level 26, down to level 20, is maintained at just about the frothing temperature of the pitch, and in this zone there is effected the initial ebullition and intumescence of the pitch and its coking is started. By operation of the discharge device, the coke is discharged from the bottom of the coke mass, and, as the mass sinks, the forming coke derived from the pitch settles lower in the retort and is subjected to the higher temperatures from the lower and hotter heating flues, thus completing the coking after the pitch mass has undergone the initial frothing stage that commonly creates difficulty in treating pitch in retorts. The level of the top of the retort charge is maintained by the running in of melted pitch from the supply tank. When the apparatus is in complete operation, each retort will thus be filled, and maintained filled, with the pitch and the forming coke therefrom, and the process will be carried on in a substantially continuous manner, the distillation and carbonization being effected as rapidly as possible and yielding a pure pitch-coke.

To facilitate the discharge of the coke, which may be somewhat impeded by the forming of large coke cakes in the lower part of the retort, the coke mass may be given a more or less stratified character by introducing at intervals, through the holes 27 in the retort lids, pulverized solid carbonaceous material, to form planes of weakness or cleavage, in the pitch coke. These holes 27 may also be utilized as inspection holes.

A like continuous process may also be practiced by maintaining all of the heating flues at substantially the same temperature, instead of graduating their heat as above described.

The foaming stage is passed soon after the pitch is introduced into the upper part of the retort, and the troublesome effects of violent foaming are obviated and are prevented from interfering with the forming of the coke and the uniform operation of the carbonizing chamber, without need for varying the heats during the coking process.

The invention is hereinabove set forth in a preferred manner in which it may be practiced, but it may of course be practiced

in other ways within the scope of the processes hereinafter claimed.

I claim:

1. In a process of coking liquefiable bituminous material; liquefying said material, feeding it upon the top of a coking mass of such material, progressively sinking said coking mass into zones of successively higher temperature, and withdrawing the finished coke from the bottom of such mass; substantially as specified.
2. In a process of coking liquefiable bituminous material: liquefying said material, feeding it into a progressively coking mass of such material, shifting the aforesaid progressively coking mass from such feed toward the discharge of the finished coke and discharging the finished coke at a point remote from that at which the liquified material is fed to the progressively moving coking mass; substantially as specified.
3. In a process of coking liquefiable bituminous material; liquefying said material and feeding it into a zone of moderate temperature to effect the initial ebullition and intumescence and start the forming of the coke, and then progressively shifting the forming coke and subjecting it to higher temperatures until its formation is completed, and withdrawing the finished coke from the final heating zone; substantially as specified.
4. In a process of coking liquefiable bituminous material: liquefying such material and feeding it upon a mass of coke subjected to heat that effects the initial ebullition and intumescence of such liquefied material and starts the coking of it, shifting the aforesaid mass of coke and the forming coke, while subjected to coking heat, towards the discharge of the finished coke, and maintaining the feeding of the liquefied material upon the forming coke and discharging the finished coke at a point remote from that at which the liquified material is fed to the progressively moving coking mass; substantially as specified.
5. In a process of coking liquefied bituminous material: the continuous feeding in and coking of the said liquefied material in mass, with continuous discharge of the finished coke from the mass; substantially as specified.
6. In a process of coking liquefiable bituminous material: liquefying said material and feeding it upon the forming coke and discharging the finished coke, and intermittently feeding into the coking mass, as it shifts towards its discharge, solid carbonaceous material, to form cleavage strata in the coke, substantially as specified.
7. In a process of coking liquefiable bituminous material: liquefying said material and feeding it upon a coking mass of said material and shifting said mass towards the discharge of the finished coke, the feeding and discharging being gauged to maintain the coking mass at a nearly constant level and discharging the finished coke at a point remote from that at which the liquified material is fed to the progressively moving coking mass, substantially as specified.
8. In a process of coking liquefiable bituminous material: liquefying said material, feeding it upon the top of a coking mass of such material, progressively sinking said coking mass vertically into zones of successively higher temperature, and withdrawing the finished coke from the bottom of such mass; substantially as specified.
9. In a process of coking liquifiable bituminous material: forming a coking column of such material, feeding a bituminous material in liquid form upon the top of said coking mass, progressively sinking said coking mass into zones of successively higher temperature, this being done by the application of a distilling heat as distinguished from a coke-consuming heat, and then withdrawing the finished coke from time to time from such mass.

In testimony whereof, I have hereunto set my hand.

FREDERICK W. SPERR, JR.
